CLAIM

The design for a container for waste motor oil, as shown and described.

DESCRIPTION

FIG. 1 top and left side perspective view of a container waste motor oil showing my new design;

FIG. 2 is a left side elevational view thereof;

FIG. 3 is a front elevational view thereof;

FIG. 4 is a top plan view thereof;

FIG. 5 is a right side elevational view thereof;

FIG. 6 is a rear elevational view thereof; and,

FIG. 7 is a bottom plan view thereof.

FIG. 1

FIG. 4

FIG. 2

FIG. 3

*FIG.5**FIG.6**FIG.7*
